CLAIM

The ornamental design for a protection relays, as shown and described.

DESCRIPTION

FIG. 1 is a perspective view of a protection relays showing my new design according to a first embodiment thereof,
FIG. 2 is a front elevational view thereof,
FIG. 3 is a rear elevational view thereof,
FIG. 4 is a top plan view thereof,
FIG. 5 is a right side elevational view thereof,
FIG. 6 is a perspective view of a protection relays showing my new design according to a second embodiment thereof,
FIG. 7 is a front elevational view thereof,
FIG. 8 is a rear elevational view thereof,
FIG. 9 is a top plan view thereof; and,
FIG. 10 is a right side elevational view thereof.

1 Claim, 6 Drawing Sheets
